TRAVERSE BAR FOR WINDING AND
SIMILAR MACHINES

Hyman Waisman, Long Island City, N. Y., assignor to Perfect Thread Co., Inc., Brooklyn, N. Y., a corporation of New York

Application March 11, 1940, Serial No. 323,317

5 Claims. (Cl. 242—35.5)

This invention relates to winding machines for winding yarn or thread on straight spools, bobbins, tubes and the like (which will be termed generally as "tubes") and tapered cops, cones and the like (which will be termed generally as "cones"), and more particularly, to machines for winding two or more tubes or cones simultaneously (on what will be termed generally as "multiple" winding machines).

10 The object of the invention is to enable multiple winding machines to wind tubes and cones of lengths greater than heretofore possible. A further object is to improve the winding of multiple tubes and cones of the lengths now wound on such machines and also of tubes and cones of increased length. A still further object of the invention is the provision of means for facilitating the adjustment of the machine for different length tubes or cones.

20 For the attainment of these and such other objects as shall herein appear or be pointed out I have shown an embodiment of my invention in the accompanying drawing, wherein:

Fig. 1 is a front view of the winding mechanism, showing particularly, the traverse bar and associated parts;

Fig. 2 is a plan view thereof;

Fig. 3 is a section taken on the line 3—3 of Fig. 2; and

30 Fig. 4 is a plan view similar to Fig. 2 but showing the winding of a pair of cones, rather than tubes.

The pair of tubes 1 and 1' are placed on the rotating spindle 2 and the thread or yarn guided 35 to wind properly on the rotating tubes, by a pair of porcelain guides, respectively, 3 and 3' provided at the upper ends of guide fingers 4 and 4' secured to the traverse bar 5 in a manner to be described more fully. The upper ends of 40 the guide fingers, near the porcelain guide, are provided with projecting tongues 4t which ride on the top edge of a presser or back plate 6, the tongues being bent over the top of the plate, as best seen in Fig. 3, to hold the fingers loosely to 45 the plate.

45 Back plate 6 is secured, as by machine screws to a balance lever 7 pivoted to the frame of the machine at 7a; the other end of the lever 7 is balanced by a counterweight 7b. As a result of 50 this construction, the counterweight urges the lever in a counterclockwise direction as viewed in Fig. 3, causing the back plate 6 to press the guide fingers and the porcelain guides against the tubes, the lever and all the parts turning clockwise as 55 the diameter of the tubes build up. The secure-

ment of the plate 6 and lever 7 is made so as to provide a slideway 8 for the traverse bar 5. The right end of the traverse bar is provided with a block 9 from which depends a pin 9p receivable in the groove 10g of drum cam 10, for the purpose of rapidly reciprocating the traverse bar.

As the traverse bar is reciprocated and the tubes, rotated, the two threads guided by the pair of porcelain guides 3 and 3' of the traverse bar, are uniformly and simultaneously wound on both tubes 1 and 1'. In multiple winding machines heretofore made, only tubes of a limited length could be wound in multiple (i. e., in double); tubes of a greater length would have to be wound on single machines, i. e., on machines having a single guide on the traverse bar. If it were attempted to wind longer tubes on a double machine, not only would the tubes be unsatisfactory but there would be caused frequent breakage of the machine, especially, the traverse bar. The back plate casting 6 is machined, 6m, on the side against which the guide fingers reciprocate. As heretofore made, the guide fingers 4 and 4' were made of steel sufficiently thin so as to be capable of adjustment relatively to the machine surface 25 6m of the back or presser plate 6 and the two tubes 4 and 4'. In spite of the accurate machining of the back plate and the adjustability of the guide fingers, it has not been practical to wind two tubes (or two cones) beyond a limited length. 30

The traverse bar of this invention is made in two separable parts, a rear portion 15' at the rear end of which is secured the pin block 9 and at the front of which is secured the guide finger 4', and a front portion 15, at the front end of 35 which is secured the other guide finger 4. The two portions are joined by a long screw connection, as by forming a long screw thread 15t on the rear portion 15' and a long tapped hole or socket 15s on the front portion 15, into which the threaded portion is screwed. The threaded screw and the tapped socket are cut so that the two fit easily. By this provision of a screw or threaded joint between the two guide fingers, an angular adjustability is provided to enable any 45 inaccuracies in the machine surface 6m or in the plate casting itself to be compensated, as well as any mis-alignment of the guide fingers. That is, each of the guide fingers may adjust itself independently of the other; hence, the position of one of the two guides is not subject to any possible inaccuracy of the plate, either of the part of the plate associated with that one of the guides or the part of the plate associated with the other 50 guide. 55

5 The screw thread serves not only to permit of this angular adjustability or compensation, but also is made sufficiently long, i. e., with sufficient thread engaging surfaces, to serve to fasten the two portions of the traverse bar together in a manner that will withstand the very considerable acceleration and deceleration forces caused by the rapid reciprocation of the traverse bar.

10 A further advantage of making the traverse bar in two parts is the facility afforded of adjusting the machine for different lengths of tubes. In multiple or double winding machines as heretofore made an entire new traverse bar is required for each length of tube to be wound. In a machine incorporating this invention, all that would be required in adjusting the machine for tubes of desired length would be to attach a front portion 15 of the prescribed length, it being understood that a set of such portions will be on hand each for a different tube length.

15 Both objects—angular adjustability and adjustment for length—are attained in machines for winding cones, as well as tubes (as illustrated in Figs. 1 and 2). The invention is applied in the same manner to cone winding, Fig. 4, in which cones 21 and 21' are being wound, the parts of the machine bearing the same reference characters as in Figs. 1 to 3, except that the back plate 20 is now provided with two machined surfaces 16m and 16m' inclined in a line parallel to that of the taper of the cones.

25 By reason of the screw or threaded joint 15s—15t, Fig. 4, between the front portion 15 of the traverse bar and the rear portion 15' thereof, the guide finger 4 may move along the machined guide surface 16m at an angle to the straight line in which the traverse bar itself reciprocates. Also, by reason of this joint and because the rear portion 15' of the traverse bar may turn to a 30 sufficient extent in its guideway 8, the guide finger 4' may move along the machined guide surface 16m' at an angle to the straight line in which the traverse bar itself reciprocates. The angle made by machined surface 16m is substantially equal to that made by 16m', with the line of 35 traverse bar travel. Moreover, because of the said joint, any difference in these angles will be compensated for.

40 While the drawing shows the application of the invention to two tubes (Figs. 1 and 2) and two cones (Fig. 4) it is evident that the invention may be applied to a machine in which three or more cones or tubes are simultaneously wound. In the case of three tubes (or cones) there would be two screw joints, one between each adjacent pair of tubes; in the case of four tubes, three joints would be required, etc.

45 I claim:

- 50 1. In a machine of the class described for winding a plurality of tubes or cones, the combination of a rotating spindle upon which the cones or tubes are mounted, a balance lever, a back plate secured to the upper arm of the said lever, a traverse bar supported in the said upper arm for reciprocating movement, means for reciprocating the same, a plurality of guide fingers equal to the number of tubes or cones, a counterweight secured to the lower arm of the said lever to press the upper arm and the said plurality of guide fingers against the tubes or cones, the said traverse bar being formed of sections equal in number to the said plurality of tubes or cones and guide fingers, one of the fingers being secured 55 to each of the bar sections, the said bar sections

being attached to each other by a threaded connection of sufficient length to withstand the acceleration and deceleration forces of the rapidly reciprocating traverse bar.

5 2. In a machine of the class described for winding a plurality of tubes or cones, the combination of a rotating spindle upon which the cones or tubes are mounted, a balance lever, a back plate secured to the upper arm of the said lever, a traverse bar supported in the said upper arm for reciprocating movement, means for reciprocating the same, a plurality of guide fingers equal to the number of tubes or cones, a counterweight secured to the lower arm of the said lever to press the upper arm and the said plurality of guide fingers against the tubes or cones, the said traverse bar being formed of sections equal in number to the said plurality of tubes or cones and guide fingers, one of the fingers being secured to each of the bar sections, the said bar sections being attached to each other by a threaded connection.

10 3. In a machine of the class described for winding a plurality of tubes or cones, the combination of a rotating spindle upon which the cones or tubes are mounted, a back plate, a traverse bar supported for reciprocating movement, means for reciprocating the same, a plurality of guide fingers equal to the number of tubes or cones, means to support the said back plate and press the same and the said plurality of guide fingers against the tubes or cones, the said traverse bar being formed of sections equal in number to the said plurality of tubes or cones and guide fingers, one of the fingers being secured to each of the bar sections, the said bar sections being attached to each other by a threaded connection of sufficient length to withstand the acceleration and deceleration forces of the rapidly reciprocating traverse bar.

15 4. In a machine of the class described for winding a plurality of tubes or cones, the combination of a rotating spindle upon which the cones or tubes are mounted, a back plate, a traverse bar supported for reciprocating movement, means for reciprocating the same, a plurality of guide fingers equal to the number of tubes or cones, means for maintaining the said back plate and the said plurality of guide fingers against the tubes or cones, the said traverse bar being formed of sections equal in number to the said plurality of tubes or cones and guide fingers, one of the fingers being secured to each of the bar sections, the said bar sections being attached to each other by a threaded connection.

20 5. In a machine of the class described for winding a plurality of tubes or cones, the combination of a rotating spindle upon which the cones or tubes are mounted, a balance lever, a back plate secured to the upper arm of the said lever, a traverse bar supported in the said upper arm for reciprocating movement, means for reciprocating the same, a plurality of guide fingers equal to the number of tubes or cones, a counterweight secured to the lower arm of the said lever to press the upper arm and the said plurality of guide fingers against the tubes or cones, the said traverse bar being formed of sections equal in number to the said plurality of tubes or cones and guide fingers, one of the fingers being secured to each of the bar sections, the said bar sections being articulated to each other to provide angular compensation.
